UNITED STATES PATENT OFFICE.

JOHN P. HALL, OF BLUFFTON, INDIANA.

SAW-GUIDE.

SPECIFICATION forming part of Letters Patent No. 254,212, dated February 28, 1882.

Application filed December 31, 1881. (Model.)

To all whom it may concern:

Be it known that I, JOHN P. HALL, a citizen of the United States, residing at Bluffton, in the county of Wells and State of Indiana, have 5 invented certain new and useful Improvements in Movable Saw-Guides; and I do hereby declare that the following is a full, clear, and exact description of the same, reference being had to the annexed drawings, making a part 10 of this specification, and to the letters and figures of reference marked thereon.

This invention relates to certain improvements in guides for circular saws; and it has for its objects to provide a device simple and 15 inexpensive in construction, which can be readily applied to the saw-frame, and which can be conveniently adjusted to the saw by the attendant without requiring him to change his position, as more fully hereinafter specified. 20 These objects I attain by the devices and mechanism illustrated in the accompanying drawings, in which—

Figure 1 represents a top view of my improved guide complete; Fig. 2, a front elevation 25 of the same; and Fig. 3, a longitudinal vertical sectional view of the guide, taken on the line *xx* of Fig. 1.

The letter A indicates the base-plate of my improved guide, which is preferably constructed 30 of cast metal, and is provided with transverse slots B, by means of which it may be adjustably secured to the saw-frame by means of suitable set-screws or otherwise. The said plate A, on its upper face, is provided with a 35 frustum-shaped boss, C, upon which is swiveled a bent lever, D, the said lever being confined thereon by means of a central screw-bolt, E, the head of which sets in a countersunk recess in the lower side of the plate A, the upper end of said bolt being screw-threaded and 40 provided with a confining-nut, F, a suitable washer, G, being interposed between the nut and the lever D, and an elastic washer, H, being interposed between the washer G and the 45 end of the boss C, by means of which the said lever is held with a yielding pressure to its seat upon the boss. The bent lever, at its free end, is bifurcated, as indicated by the letter I, and provided with an approximately circular 50 opening, K, as shown in Fig. 1. The members of the bifurcated portion of the said lever

are bored transversely, and are provided with adjusting-pins L, which are held in position by means of set-screws M.

To the inner side of the lever D is secured 55 or cast with it a lug, O, which is bored vertically, and forms a bearing for a short journal, P, which carries a female screw-threaded nut, R, with which engages a male screw-thread formed on the end of an adjusting-shaft, T. 60 The said shaft, near its free end, is provided with an annular groove, U, and is journaled in a vertically-slotted stud, W, secured to or cast with the frame A. The free end of said shaft terminates in a cross-head, Y, thumb-button, 65 or other device, by means of which the shaft may be conveniently turned to adjust the lever to the saw.

The journal P is confined in its bearing in the present instance by means of a transverse 70 spring-pin, Z, and the shaft T by means of a similar pin, A'; but it is evident that other means may be employed for this purpose, if desired.

The operation of my invention will be readily 75 understood in connection with the above description, and is as follows: The plate A is secured to and adjusted upon the saw-frame by means of suitable screws or bolts passing through the slots B, the edge of the saw passing 80 between the bifurcated members of the bent lever D. The pins L are then properly adjusted to guide the saw. When the saw is in operation, should any further adjustment become necessary, this can be effected by simply turning the adjusting-shaft in the proper 85 direction without stopping the saw or requiring the attendant to change his position.

The advantages of my invention will be apparent, as it will be seen that the device is constructed virtually of two parts, A and D, and the adjusting mechanism, making it compact, solid, and durable, and reducing its cost to a minimum, while it can be adjusted to guide the saw with the greatest nicety with but little 95 trouble. Moreover, owing to the simplicity of its construction, it is not liable to get out of order, and if it becomes impaired it can be readily repaired at small cost.

Having thus described my invention, what 100 I claim, and desire to secure by Letters Patent, is—

1. The base-plate A, having the lever D pivoted on a boss projecting therefrom, and having at its bifurcated end the lug O, in combination with the screw-nut R, connected thereto, 5 and the adjusting screw-shaft T, substantially as and for the purpose set forth.

2. The base-plate A, cast with the frustum-shaped boss C, in combination with the lever D, constructed as described, and having screw- 10 nut R, to operate in connection with the adjusting screw-shaft T, and means, substantially

as shown, for connecting said lever to the base-plate, substantially as and for the purpose set forth.

In testimony that I claim the above I have 15 hereunto subscribed my name in the presence of two witnesses.

JOHN PHILIX HALL.
